Patented Feb. 26, 1974

230,494

SET OF CHESS PIECES

Elbert F. Elam, 17620 Talford Ave.,
Cleveland, Ohio 44128

Filed July 28, 1971, Ser. No. 167,087

Term of patent 14 years

Int. Cl. D21—01
U.S. Cl. D34—5 CH

Fig. 1

Fig. 2

Fig. 3

Fig. 4

Fig. 5

Fig. 6

Fig. 8

Fig. 10

Fig. 7

Fig. 9

FIG. 1 is an elevation view of the pawn which is the same from all sides;

FIG. 2 is a side elevation view of the knight;

FIG. 3 is a front elevation view of the knight;

FIG. 4 is an elevation view of the queen which is the same from all sides;

FIG. 5 is a front elevation view of the bishop;

FIG. 6 is a side elevation view of the bishop;

FIG. 7 is an elevation view of the rook which is the same from all sides;

FIG. 8 is a top plan view of the rook;

FIG. 9 is a side elevation view of the king which is the same from all sides; and,

FIG. 10 is a top plan view of the king.

The top of FIGS. 1, 5 and 6 are plain as seen in FIG. 3, and the top view of FIG. 4 is the same as FIG. 10 without the square center.

I claim:

The ornamental design for a set of chess pieces, as shown and described.
